CLAIM

The ornamental design for a toy vehicle, as shown and described.

DESCRIPTION

FIG. 1 is a perspective view from above, to the front and to the left side of the new design for a toy vehicle;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view from above, to the front and to the left side thereof, optionally modified to mount a scooter. In the drawings, the broken lines are for the purpose of illustrating portions of the article that form no part of the claim.
